UNITED STATES PATENT OFFICE.

KARL F. NYSTROM, OF CHICAGO, ILLINOIS.

DRAFT-GEAR KEY-RETAINING MEANS.

Application filed July 27, 1925. Serial No. 46,234.

My invention relates to means for retaining the usual coupler and draft gear keys in place against accidental loss or undesired removal; the invention having for its object 5 the provision of means which may not only be readily applied to the keys, and which may be employed with draft gears or rigging as now generally employed in standard railroad construction, but which may be 10 cheaply manufactured, at a cost materially less than the present cost of renewing of the cotter pins at present employed for such purpose.

Another object of the invention is the 15 provision of means of such character as to withstand the strains and shearing action encountered in actual service or operation and therefore a construction which eliminates the possibility of the draft keys shifting or working out of place and thereby causing accidents and delay, as has been the case with the constructions at present in use wherein ordinary cotter pins are employed.

25 A further object of my invention is to provide means which is so constructed as not to become wedged or bound in any particular position by reason of the strains and movements encountered during operation of the car; while at the same time being of such formation that the cost of fabrication of both the key and the retaining means may be materially less than such cost of the devices at present employed.

35 The above enumerated objects and advantages, as well as others, will all be more fully comprehended and understood from the description of the accompanying drawing, wherein:—

40 Figure 1 is a sectional plan view of the center sills and draft rigging of a railroad car with my improved draft key retaining means.

Figure 2 is a cross sectional view taken 45 on the line 2—2 of Figure 1 looking in the direction of the arrows.

Figure 3 is a detail perspective view of a draft rigging or coupler key adapted to receive my improved retaining means.

50 Figure 4 is a detail perspective view of my improved retaining means.

As an exemplification of my invention, I have shown its application to the coupler or draft keys of a well known type of draft gear; the drawing disclosing at 10, 10 the usual beams arranged in spaced relation and

constituting the center sill of a car; the beams being usually provided with cheek-plates or reenforcing members as at 11.

Longitudinally movable between the center sill members 10, 10 are the usual coupler 60 12 and the yoke member 13 of the draft rigging.

As the draft rigging per se does not constitute a part of my invention, a more specific 65 illustration and description thereof need not be entered into and for that reason the springs and correlated elements are not shown.

The coupler and follower members of the 70 draft gear or rigging are movably held in place and in proper relation by means of the draft keys 14, 14, which pass through suitable slots or openings in the coupler and draft rigging members or yoke and the 75 center sill members and cheek-plates or reenforcing members as shown at 15 in Figure 1; the slots in the center sill and reenforcing members or plates being of length greater than the width of the keys 14.

80 It has been generally customary to prevent removal of draft rigging keys, such as indicated at 14 by what are generally designated as hairpin cotter, which are usually inserted through small holes adjacent to the 85 tapered end of the key; the other end of the keys usually being provided with a headed portion to limit and prevent further movement of the key through the corresponding draft or center sill slots.

Because of the relatively small diameter of the hairpin cotters and the relatively great thickness or depth of the keys, it has been difficult to punch the cotter holes in said keys, there not being sufficient material in the 95 punch to withstand the force necessary to punch the hole through metal of such thickness. On this account, it has been found generally necessary to drill the holes for the hairpin cotters through the draft rigging 100 keys, thereby entailing a relatively large expense and time in operation.

My invention contemplates the use of a pin 16 as shown in detail in Figure 4 of comparatively great thickness or diameter, 105 to be inserted through the hole in the tail or tapered end of the key 14. The pin 16 is preferably round in cross-section and provided with a head 17 which is also preferably of the oblong or elongated form shown in 110 Figure 4 so as to provide a suitable sized head and at the same time enable easy inser-

tion of the pins with the slight amount of clearance between the key slot and the center sills or reenforcing plates thereon. The ends of the head portion 17 are preferably slightly rounded as shown at 18 so as to prevent the pin binding or becoming wedged against the sides of the sill members.

By reason of the pin 16, the draft keys necessarily are provided with a comparatively large hole, as shown at 19 in Figure 3.

With my invention, considerable saving is effected by making a hole or aperture in the end of the draft rigging key by a punching, or preferably a plurality of punching operations, thereby greatly decreasing the cost of such operation. Not only is the cost of forming the retaining means apertures decreased by substituting punching for drilling operations, but a further saving is effected by utilizing only one retaining means apertured in an end of a key, rather than two, as has been customary heretofore.

More specifically stated, the preferred form of my retaining means for draft rigging keys comprises the pin 16 formed with a stem or shank of relatively large diameter compared with hairpin cotters generally employed for the purpose. The head 17 of relatively large and elongated formation is preferably used, with the ends of said head being preferably rounded as stated and as shown at 18, for the reason heretofore mentioned; although it is obvious that I do not wish to be limited to this detail, as a generally elongated or rectangular form of head may be employed, if desired.

The lower end of the shank of the pin 16 is preferably provided with a hole or opening 20 for the reception of an ordinary cotter pin as shown at 21, for the purpose of preventing accidental removal of the pin 16; although the size and formation of the pin would ordinarily prevent its accidental removal and loss.

To assemble my retaining device with a key 14 of ordinary construction, the hole or aperture 19 is punched in the end of said key, the pin 16 inserted in said aperture and locked in place by means of a cotter 21 inserted through the aperture 20 of the pin. The aperture 19 in the key is preferably formed near enough to the respective center or draft sills so that when the retaining pin 16 is in place there is not room enough between the aperture and the sill to allow the pin to turn completely around with respect to the key. By virtue of this construction, undue wear between the pin 16 and the key 14 is obviated.

The ends of the pin head, as illustrated in Figure 4, are preferably rounded so that if the pin head should become turned so as to engage the side of the draft or center sills such engagement would effect a repositioning or turning back of the pin head to its

original position. When one side of the pin head has become unduly worn by rubbing engagement against the draft sills, the cotter 21 may be removed from the pin, the pin taken out of aperture 19 in the key and turned around to present the other elongated and relatively flat side of its head 17 toward the corresponding draft sill. Such reversibility makes it possible to use the retaining pin for a greater length of time than would otherwise be feasible.

My invention provides an advantageous form of retaining device, especially adapted for draft rigging keys; a device which can be easily and cheaply applied to the key and which is adapted for long service, because of its reversibility and because it presents a relatively large area of metal for engagement with the draft or center sill, thereby preventing a concentrated area of wear against the draft sill.

By virtue of the elongated head on the retaining pin, complete turning of said pin with respect to the key is generally prevented, as heretofore explained, although the pin is allowed to angle so as to always present a side of relatively large area toward the draft sill or cheek plate thereon. On account of its relatively large diameter, the pin has ample strength for resisting the shearing strains to which it is generally subjected in service.

The aperture in the stem or shank of the retaining pin 16, for receiving the cotter 21, is advantageously formed, as illustrated, parallel to the longitudinal center line of the pin head. Such a construction protects the cotter, whose dimensions are preferably less than those of the head, from wearing engagement with a sill or cheek plate thereon.

With constructions as heretofore employed, namely employing cotter-pins for locking the draft keys in place, considerable loss and difficulty has been encountered, because the relatively small cotter-pins are sheared off by the constant shearing or frictional engagement with the center sills or reenforcing or cheek-plates secured to the sills. This has not only resulted in constant loss of cotter-pins, but has also resulted in the loss of the draft-keys, which has also caused a serious disarrangement of the draft rigging, allowing the various elements to drop down onto the track, thereby causing derailment and possible injury, as well as delay. With my relatively large retaining pin, it is evident that this difficulty has been overcome; and while I believe the construction as shown to be the best embodiment of the invention, certain modifications may be made without, however, departing from the spirit of my invention.

What I claim is:—

1. In combination, a draft key provided with a circular opening near one end there-

- of, a retaining pin inserted through said opening, having a shank circular in cross-section and of a size to substantially fill said opening, said pin being provided with an 5 elongated head having rounded ends, adapted to extend transversely of the draft key and having flat surfaces to be presented toward the draft sills of a car, the lower end of the pin being apertured in a direction 10 parallel with the longer dimensions of said head, and a cotter pin disposed through said aperture.
2. In combination, a draft key provided with an opening therethrough, and a retaining pin having a round shank of relatively large diameter and provided with an oblong head, with the width of the head equal to the diameter of the shank to provide a large bearing surface disposed throughout the 15 head and shank.
3. In combination, a draft key provided with an opening therethrough adjacent one end, a round retaining pin of relatively large diameter and provided with an oblong head, the sides of the head being flush with the adjacent sides of the shank, and means secured to the lower end of the pin for retaining the pin in place.
4. A draft key having a circular aperture 20 adjacent its end, and a T-bolt adapted to enter and turn within the aperture, such bolt having an elongated head.
5. A draft key having a circular aperture adjacent its end, a T-bolt adapted to enter and turn within the aperture, such bolt having an elongated head, and means for retaining the bolt in place.
6. In combination, a draft key provided 25 with a circular opening near one end thereof, of, a draft key retaining pin inserted through said opening, the shank of said pin being of a size to substantially fill said opening, said pin being provided with an elongated head of a width approximately equal to the 30 thickness of the shank of the pin and of a length somewhat greater than the width thereof, the shank of the pin being arranged to protrude through the said draft key, and means for preventing loss of said pin, said means being engageable with the protruding 50 portion of the shank of the pin, and being arranged in a direction lengthwise of the head of said pin.
7. In combination, a key having an apertured end, a pin of circular cross section and of relatively large diameter, provided on one end with a relatively large elongated head, inserted in said aperture, the other end of said pin being perforated, and cotter means 55 extending therethrough for preventing loss thereof.
8. In combination, a draft rigging key having adjacent one end thereof a relatively large circular aperture and a pin of circular cross section and corresponding diameter 60 inserted in said aperture, said pin being provided with a relatively large elongated head presenting a relatively large flat surface toward the opposite end of the key, the other end of the pin being apertured for the re- 65 ception of locking means.
9. In combination, a draft rigging key having adjacent one end thereof a relatively large circular aperture, a pin of circular cross section and corresponding diameter 70 inserted in said aperture, said pin being provided with a relatively large elongated head provided with rounded ends presenting a relatively large flat surface toward the opposite end of the key, the other end of the 75 pin being apertured for the reception of locking means, and a cotter pin inserted in said aperture.
10. In combination, a relatively flat draft rigging key provided with a relatively large 80 aperture near one end thereof extending between upper and lower flat surfaces thereon, and a pin of corresponding size inserted in said aperture, and an elongated head of relatively large size on one end of said pin, the other end being provided with a cotter- 85 receiving aperture.
